(57) **CLAIM**

An ornamental design for a disinfectant liquid dispenser, as shown and described.

DESCRIPTION

FIG. 1 is a perspective view of a disinfectant liquid dispenser, showing my new design;

FIG. 2 is a front view thereof;

FIG. 3 is a rear view thereof;

FIG. 4 is a right-side view thereof;

FIG. 5 is a left-side view thereof; and,

FIG. 6 is a top view thereof.

A bottom view is omitted because it is plain and unornamental and forms no part of the subject matter of the claimed design. The broken lines show portions of the disinfectant liquid dispenser that form no part of the claimed design.
